(57) **CLAIM**

The ornamental design for the front panel for rack mounted video device, as shown and described.

DESCRIPTION

FIG. 1 is a front elevation view of a first embodiment of a front panel for rack mounted video device.

FIG. 2 is a top view of the first embodiment of the front panel for rack mounted video device, the bottom view being a mirror image thereof.

FIG. 3 is a left side elevation view of the first embodiment of the front panel for rack mounted video device.

FIG. 4 is a right side elevation view of the first embodiment of the front panel for rack mounted video device.

FIG. 5 is a front elevation view of a second embodiment of a front panel for rack mounted video device.

FIG. 6 is a top view of the second embodiment of the front panel for rack mounted video device, the bottom view being a mirror image thereof.

FIG. 7 is a left side elevation view of the second embodiment of the front panel for rack mounted video device; and, FIG. 8 is a right side elevation view of the second embodiment of the front panel for rack mounted video device.

The broken lines shown are included for the purpose of illustrating portions of the article and form no part of the claimed design.
